UNITED STATES PATENT OFFICE

171,218

COMBINATION CASH TRAY AND CARRIER

John McCaffrey, Oakland, Calif.

Application November 25, 1952, Serial No. 22,427

Term of patent 14 years

(Cl. D87—3)

To all whom it may concern:

Be it known that I, John McCaffrey, a citizen of the United States, residing at Oakland, in the county of Alameda and State of California, have invented a new, original, and ornamental Design for a Combination Cash Tray and Carrier, of which the following is a specification, reference being had to the accompanying drawing, forming part thereof.

Fig. 1 is a side elevation of a combination cash tray and carrier showing my new design.

Fig. 2 is an end elevation.

Fig. 3 is a top plan view.

Fig. 4 is a bottom plan view.

Fig. 5 is a top plan view of the cash tray and carrier in open position.

Fig. 6 is a transverse section through the cash tray and carrier, shown fragmentarily.

The side and end opposite those shown in Figs. 1 and 2 are identical to the side and end shown.

I claim:

The ornamental design for a combination cash tray and carrier, as shown and described.

JOHN McCAFFREY.
